H. S. Kiee Attorney

UNITED STATES PATENT OFFICE.

HARRY BUNCE, OF EAST ISLIP, NEW YORK.

HEAT-CONSERVER FOR GAS-STOVES.

1,225,761.

Specification of Letters Patent. Patented May 15, 1917.

Application filed August 21, 1916. Serial No. 116,034.

To all whom it may concern:

Be it known that I, HARRY BUNCE, a citizen of the United States, residing at East Islip, in the county of Suffolk, State of New York, have invented a new and useful Heat-5 Conserver for Gas-Stoves; and I do hereby declare the following to be a full, clear, and exact description of the invention, such as will enable others skilled in the art to which 10 it appertains to make and use the same.

The present invention relates to certain new and useful improvements in cooking stoves of that general type which are designed to burn gas, the object of the invention 15 being to provide a stove of this character which embodies novel features of construction whereby the heat from the burner is confined and concentrated within a heat chamber, thereby preventing the loss of heat 20 which is incident to the use of open burners, and enabling a single burner to do the work which is ordinarily done with several burners, with the result that there is a great saving 25 in the consumption of gas.

Further objects of the invention are to 30 provide a device of this character which is comparatively simple and inexpensive in its construction, which can either be applied as an attachment to an ordinary gas stove or 35 built into a special stove, which can be easily manipulated, and which enables all kinds of cooking to be performed in the same manner as upon an ordinary stove.

With these and other objects in view, the 40 invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a perspective view of a heat 45 conserving attachment constructed in accordance with the invention, showing the same as fitted upon the top of an ordinary gas stove.

Fig. 2 is a vertical longitudinal sectional 50 view through the same.

Fig. 3 is a horizontal sectional view.

Fig. 4 is a bottom plan view.

Fig. 5 is a diagonal view through one of 55 the corners, taken on the line 5—5 of Fig. 3.

Fig. 6 is a side elevation of a cooking stove embodying the invention.

Fig. 7 is a top plan view of the same with one of the lids removed.

Corresponding and like parts are referred to in the following description and indicated 60 in all the views of the drawings by the same reference characters.

The idea of the invention is to conserve the heat from a single burner by the provision of a shallow casing which is arranged over 65 the burner, said casing having suitable cooking openings in the top thereof which are closed by tightly fitting lids, and dampers being provided on the interior of the casing for subdividing the same into a series of 70 small heat chambers when desired. This casing, as shown by Fig. 1, may be constructed to be used as an attachment upon an ordinary gas stove A. The casing has substantially the same size and configuration as the 75 top of the gas stove, and is comparatively shallow in depth, the top 1 thereof being provided with a series of cooking openings 2, while the bottom 3 thereof is provided with an opening 4 to fit over one or more of the 80 burners of the stove A. The side walls 5 are provided with a layer 6 of asbestos to more effectively conserve the heat, and the front of the casing is provided with an air inlet opening 7 for supplying air to the burner. 85 A series of small air inlet openings 8 are arranged in the side walls 5 of the casing at a point toward the bottom thereof, said openings being too small in size and located too near the bottom of the casing to interfere 90 with confining and concentrating the heat from the burner in the contemplated manner. The cooking openings 2 are provided with tightly fitting removable lids 9 which are kept in position at all times except when a 95 cooking utensil is applied to one of the openings.

Corresponding forwardly and rearwardly extending damper plates 10 are provided upon opposite sides of the bottom opening 4, 100 said plates being hinged at 11 to the bottom and being adapted to be swung upwardly into engagement with the top and side walls to cut off the heat from the ends of the casing. When these dampers 10 are swung upwardly into operative position the heat from the burner is confined within a small heat chamber, thereby eliminating the necessity of heating the entire casing when only one or two of the cooking holes 2 are to be 105 used. These dampers 10 may be operated in any suitable manner as by means of plun-

ger rods 12 which extend transversely across the casing in opposite directions and project through openings 13 provided in the side walls 5 of the casing. By pulling upon these plunger rods 13 the dampers 10 can be swung upwardly into operative position, and the front and rear walls of the casing may be provided with inwardly extending stop flanges 14 for engagement with the said dampers when they are in a vertical position. The extremities of the operating rods 12 may terminate in weights 15, said weights being adapted to be used as handles, and also serving to hold notches 16 provided in the plungers in engagement with edges 17 for the purpose of locking the dampers in an adjusted position.

Extending transversely between the dampers 10 and arranged to the rear of the opening 4 in the bottom of the casing is a third damper 18 which is hinged at 19 to the bottom of the casing. A rock shaft 20 extends laterally through one side of the casing and is connected to the damper 18 for swinging the same upwardly and downwardly. A small crank handle 21 may be provided for operating the rock shaft, and this crank handle may have a spring formation so as to yieldably engage a segmental rack bar 22 to hold the damper in an adjusted position. The provision of this third damper 18 admits of a still smaller chamber being provided for confining and concentrating the heat, so that all waste of fuel can be avoided when there is but a single one of the cooking holes 2 to be used.

The interior corners of the casing 1 may be provided with curved deflectors 23 for concentrating the heat at the top of the casing and preventing waste thereof at the angular corners. For baking purposes an oven D would be used, said oven being of the conventional construction, with the exception that it has an open bottom so that it can be placed over one or more of the cooking openings 2.

In Fig. 6, the invention is shown as built into a special stove, thereby providing a complete unit for cooking purposes. The construction is practically identical with that previously described, with the exception that the bottom 3 of the casing forms the top of a suitable stand C, and there is no need to provide the opening 4, since a single burner B is arranged within the cas-

ing between the two side dampers 10 and the transverse rear damper 18. In all other respects the construction and manner of operation is identical with that previously described.

Having thus described the invention, what I claim as new and desire to secure by Letters Patent, is:—

1. A cooking stove including a gas burner, a shallow casing arranged over the gas burner and inclosing a heat conserving chamber, the top of the casing being provided with a series of cooking openings, removable lids for the cooking openings, a pair of substantially parallel dampers extending across the casing on opposite sides of the burner and arranged to shut off the end portions of the casing from the middle portion thereof, a transverse damper extending between the parallel dampers on one side of the burner for further reducing the size of the heat chamber, and means for operating the said dampers.

2. A cooking stove including a gas burner, a shallow casing arranged over the gas burner and inclosing a heat conserving chamber, the top of the casing being provided with a series of cooking openings, removable lids for the cooking openings, a pair of substantially parallel dampers extending across the casing on opposite sides of the burner, said dampers being hinged to the bottom of the casing and being adapted to be swung upwardly into engagement with the top thereof to shut off the end portions of the casing from the middle portion thereof, transversely extending operating rods connected to the dampers and extending through the sides of the casing for manipulating the dampers, a transverse damper extending between the parallel dampers on one side of the burner for further reducing the size of the heat chamber, a rock shaft extending along the bottom of the casing and carrying the transverse damper, and means for rotating the rock shaft to move the transverse damper into operative and inoperative positions.

In testimony whereof I have signed my name to this specification in the presence of two subscribing witnesses.

HARRY BUNCE.
